RECLINING SELF-ADJUSTING CHAIR

Leon L. McKinney and Lucius H. McKinney,
Hartford, Conn.

Application December 26, 1945, Serial No. 637,218

1 Claim. (Cl. 155—67)

1

This invention relates to certain new and useful improvements in a reclining self-adjusting chair.

One of the principal objects of the present invention is to provide a reclining self-adjusting chair of complete steel construction to give strength and rigidity thereto, with the exception of the canvas seat, back, and leg rest.

Another object of the invention is to provide a reclining self-adjusting chair that includes a ground-supported stand upon which the swinging chair per se is pivotally suspended with the chair comprised of back, seat, and leg bars hingedly connected in a manner whereby a person seated therein will by body pressure convert the chair from an upright to a reclining position.

A further object of the invention is to provide a chair structure of the foregoing character wherein a ground-supported stand pivotally supports a reclining chair that is formed of hingedly connected back, seat, and leg portions, with a foot bar at the lower ends of the leg portions adapted in the presence of pressure exerted thereon by an occupant of the chair to effect pivotal movements of the chair bars to cause the chair to be converted from an upright to a reclining position.

It is a further object of the invention to provide a reclining self-adjusting chair wherein a pivotally suspended chair frame comprised of hingedly connected back, seat, and leg bars has a canvas strip adjustably mounted at opposite ends upon the back and leg bars for the positioning of such strip comfortably to suit occupants of different weights.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a side elevational view of a reclining self-adjusting chair constructed in accordance with the present invention.

Figure 2 is a front elevational view of the chair.

Figure 3 is a detail perspective view of the foot rest with portions of the legs of the chair illustrated by dotted lines.

Figure 4 is a vertical cross-sectional view showing the chair in upright position in full lines and in reclining position in dotted lines and illustrating the manner of attaching the canvas back, seat, and leg rest to the chair per se.

Figure 5 is a fragmentary perspective view

2 showing the pivotal support between opposite sides of the chair and the supporting stand.

Figure 6 is a vertical cross-sectional view taken on line 6—6 of Figure 2, showing the mounting of a canopy on the supporting stand of the chair.

Figure 7 is a top plan view with the canopy pole shown in section, and

Figure 8 is a detail sectional view showing the lower ends of the leg portions of the chair per se, with the adjustably mounted cross rod for the attachment of the lower end of the canvas seat portion of the chair.

Referring more in detail to the accompanying drawings, the reclining self-adjusting chair comprises a ground-supported stand with a chair per se pivotally suspended between side portions of the stand, the latter comprising a pair of spaced members forming the side portions of the stand with each side portion having a lower horizontal bar 10 twisted and rolled at its ends to provide ground-engaging feet. A perpendicular rod 12 rises from the horizontal bar 10 intermediate the ends thereof and is anchored thereto as at 13 and a pair of upwardly converging rods 14 anchored at their lower ends as at 15 respectively adjacent the feet 11 are secured at their upper ends by the rivet 16 to the perpendicular rod 12 adjacent its upper end. The connection between the two side frame members of the ground-supporting stand includes a pair of truss rods 17 arranged in crossed relation and anchored together at their crossing points by a rivet 18 with the spaced divergent ends anchored by rivets or nut and bolt combinations 19 to the perpendicular rod 12. With a structure of the foregoing character a strong and substantial ground-supporting frame is provided for the pivotally suspended reclining chair that is disposed between the side members of the stand.

The reclining chair per se is also of metallic construction, except for the canvas seat portion and comprises a pair of back bars 20, a pair of seat bars 21, and a pair of front leg bars 22. A cross rod 23 extends between the upper ends of the back bars 20 and is selectively mounted and retained in spaced openings 24 in said bars for purposes presently to appear. The lower ends of the back bars are pivotally connected as at 25 to the seat bars 21 adjacent their rear ends and the rear ends of said seat bars are arched downwardly as at 26. A cross rod 27 extends between the front leg bars 22 below the upper ends thereof and the forward ends of the seat bars 21 are pivotally supported on the cross rod 27. A second cross rod 28 extends between the seat bars 21 slightly rearwardly of the cross rod 27. A

second cross rod 29 extends between the front leg bars 22 at points spaced upwardly of the lower ends thereof and is selectively mounted in openings 30 in the leg bars for purposes presently to appear.

Arm supporting bars are pivotally connected as at 32 at their forward ends to the upper ends of the front leg bars 22, while their rear ends are pivotally connected as at 33 to the back bars 20 at points above the pivot points 25, the arm supporting bars 31 being parallel with the seat bars 21 and forming therewith a parallelogram in both upright and reclining positions of the chair.

The pivotal support for the reclining chair per se on the ground-supporting stand is shown more clearly in Figures 5 and 6 and comprises a pair of suspension bars 34 and 35 respectively connected at their lower ends as at 36 to the arm supporting bars 31 and the pivotal connection 38 between the back bars 21 and the arm supporting bars 31, while their upper ends straddle and are pivotally connected as at 37 to the upwardly arched and downwardly and inwardly bent upper end 38 of the perpendicular rod 12. It will be noted that the suspension bars 35 are of angular formation to provide arm space adjacent the back portion of the chair.

As illustrated more clearly in Figure 4, the canvas back, seat and leg rest portion of the chair comprises a back portion looped around and anchored as at 40 to the cross rod 23 at the upper ends of the back bars 20, the canvas strip adjacent the rear ends of the seat bars being folded upon itself and stitched together as at 41 to form a loop 42 that is anchored to the cross rod 43 extending between the lower ends of the arched portions 26 of the seat bars 21. From the stitched portion 41 of the canvas extends the seat portion 44 thereof that freely extends over the cross rods 28 and 27 and is then directed downwardly to form a leg rest portion 45 that is looped at its lower end as at 46 to inclose the cross rod 29 adjacent the lower ends of the front leg bars 22. It will be understood that by adjusting the cross rods 23 and 29 respectively in the back and leg bars 20 and 22, the seat may be thrown to either the front or rear to compensate for the weight of the occupant of the chair. Also, the degree of reclining movement of the chair may be limited by the placement of pins in selected openings 47 formed in the front leg portions slightly above the cross rod 27 with the pins engageable with the seat bars 21 to limit such reclining movements.

A substantially U-shaped foot rest 48 has the side leg portions 49 thereof pivotally mounted as at 50 upon the lower ends of the front leg portions so that by exerting leg pressure on the foot rest and back pressure on the chair back, the latter is automatically shifted from an upright to a reclining position. In event of a chair occupant being unable to reach the foot rest 48, an auxiliary U-shaped rest 51 has its slide legs pivotally mounted as at 52 upon the side legs 49 of the main foot rest.

In the above assemblage, the second cross rod 28, although seemingly inactive, provides an important service in maintaining the freedom of operation. This will be understood from the fact that the skeletonized framing of which the seat structure is composed is so formed that each of the members of the quadrangular side formations are connected for pivotal movement to permit the movements between upright and reclining

positions. The skeletonized formation tends to limit the bearing possibilities and this, due to the length of the span between the front cross rod 27 and the cross rod 43, can tend to affect the articulating movements of the framing. Cross rod 28, having no pivotal movement action, but fixedly connecting the front portions of the seat bars, holds the latter against spreading or other lateral movement through the fixed and permanent spacing provided by rod 28, the latter equalizing the relationships set up through the presence of the quadrangular side frames. As a result, the movements of the pivoted members are maintained uniformly similar, thus assuring proper operation of the assembly despite the skeletonized formation of its members.

While the cross rod 28 tends to provide a rigid support at the front of the seat additional to that provided by cross rod 27, the two rods are sufficiently close together as to not materially affect the seating or reclining postures of the user. In fact, the presence of rod 28 is actually serviceable in this connection through the fact that the seat portion which overlies rod 27 and which would normally be subject to wear conditions due to the abrupt bend around the rod, is instead led rearward in constant direction with the latter then continued as the regular seating direction, thus preventing any effect on the seat tending to cause excessive wear under service conditions.

A pair of vertically spaced tubular guide straps 53 are anchored as at 54 to one of the perpendicular rods 12 for the reception of the stand pole 55 of a canopy 56 that overlies the chair. An article-supporting tray 57 is carried by a clamp attachment 58 engageable with the perpendicular rod 12 at the opposite side of the stand.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

We claim:

50 In a reclining, self-adjusting chair of the character described, a ground supported stand comprising vertical side frame members and cross struts connecting the same, a self-adjusting reclining chair pivotally suspended between the 55 frame members at the upper ends thereof, said chair having pivotally connected back, seat and front leg frame bars and arm rests for the chair comprising bars pivotally connected to the back bars above their lower ends and to the upper ends 60 of the front leg bars in parallel with the seat bars, said seat frame bars having extensions projecting outwardly and downwardly from the point of pivotal connection of said back and seat frame bars, the upper ends of said back frame bars having a plurality of spaced apertures therein and a cross rod therebetween movably secured in said apertures, the lower ends of said leg frame bars having a plurality of spaced apertures therein and a cross rod therebetween movably secured in said apertures, a cross rod fixedly secured to the free ends of the extensions of said seat frame bars, a cross rod fixedly secured to the seat frame bars adjacent the forward ends thereof, a fabric strip having one end looped over said upper back frame cross rod, its opposite

end looped over said lower leg frame cross rod, and a loop intermediate said ends encompassing said seat frame extension cross rod, said adjustable upper and lower cross rods in conjunction with said intermediate loop permitting the seat portion of said fabric strip to be moved forwardly or backwardly relative to said frame bars and thus vary the center of gravity of said chair when occupied and provide adjustment in balance to fit variations in individual users.
